GAME BOARD

Joseph C. Dean, Jr., Winston-Salem, N. C.

Application February 28, 1956, Serial No. 40,395

Term of patent 7 years

(Cl. D34—5)

The figure is a plan view of a game board, showing my new design.

The game board is of conventional thickness.

I claim:

The ornamental design for a game board, substantially as shown and described.
